UNITED STATES PATENT OFFICE.

GRACE PFEIL, OF CHICAGO, ILLINOIS.

CORSET.

1,007,602.

Specification of Letters Patent. Patented Oct. 31, 1911.

Application filed November 1, 1909. Serial No. 525,826.

To all whom it may concern:

Be it known that I, GRACE PFEIL, a citizen of the United States, residing at Chicago, in the county of Cook and State of Illinois, 5 have invented certain new and useful Improvements in Corsets, of which the following is a specification.

With the ordinary corset, as is well known to those skilled in the art, there is ordinarily 10 an open space between the margins that is bridged merely by the lacings, and into this space the adjacent portion of the wearer protrudes. It has been proposed in the prior art to cover this space with a shield 15 that extends behind the lacings, the shield being attached at one edge to one margin of the corset, and having its other edge free. This has proven objectionable, in that it is difficult to properly position the shield; 20 the same becomes wrinkled and misplaced, so that it does not properly perform the desired function, and furthermore becomes uncomfortable to the wearer.

The present invention is an improvement 25 upon this prior art, and the object is to provide a shield, so mounted on the corset that it will at all times bridge the otherwise open space; will be comfortable to the wearer, and at the same time, will not interfere with the ready connection and disconnection of the margins of the corset.

In the accompanying drawings:—Figure 1 is a perspective view of the front of the corset. Fig. 2 is a perspective view of the 35 back of the corset. Fig. 3 is a sectional front view of the corset with parts broken away. Fig. 4 is a section on dotted line $a-a$, Fig. 3.

Similar reference numerals designate corresponding parts in all the figures of the 40 drawings.

In the embodiment disclosed, the corset, in so far as the general structure is concerned, is well known, comprising a body that opens 45 at the front, having a margin 1 provided with eyelets 2 and a coacting opposite margin 3 provided with eyes 4. A strip 5, detachably coacting with the margin 3, has studs 6 that detachably interlock in the eyes 50 4. This strip 5 furthermore has eyelets 7, and a lace 8, passing through the eyelets 2 and 7, adjustably connects the strip 5 with the margin 1.

As already explained, the corset, as thus far described, is open to the objection that 55 the space between the margin 1 and the strip 5 permits the adjacent portion of the person to protrude, and it is across this space that it is proposed to place the above described shield. In the present instance, a shield, as 60 9, is employed, said shield having a flexible section 10 secured to the rear face of the margin 1, and a flexible section 11 secured to the edge of the strip 5, as clearly shown in Fig. 4. The central portion of this shield, 65 directly in rear of the lacing, is preferably reinforced with vertically arranged stays 12. With this construction, it will be evident that the space between the margin 1 and the strip 5 can be varied, as desired, or as 70 found necessary, and this space will at all times be bridged by the shield. The flexible sections 10 and 11 permit the ready adjustment of the lacing. At the same time, the shield will at all times be properly positioned, because of its connection with the margin 1 and the strip 5, and will likewise remain in smooth and comfortable condition on the wearer. In addition, it is to be noted that the shield, being secured to the strip 5, 80 does not in any manner interfere with the opening and closing of the corset, as said strip 5 can be connected to and disconnected from the margin 3, without in any manner displacing the lacing or shield. 85

From the foregoing, it is thought that the construction, operation and many advantages of the herein described invention will be apparent to those skilled in the art, and it will be understood that various changes in 90 the size, shape, proportion, and minor details of construction, may be resorted to without departing from the spirit or scope of the invention.

Having thus fully described my invention, 95 what I claim as new, and desire to secure by Letters Patent, is—

A corset, comprising a body having eyelets in one margin, a strip separate from the body and also having eyelets, means for 100 detachably connecting the strip to the other margin of the body, a lace passing through the eyelets of the first mentioned margin and strip for adjustably connecting the same, and a shield bridging the space between the 105 strip and the margin of the body having the

eyelets, said shield being disposed behind the lace and connected directly to said margin and the strip to permit the adjustment of the lace and at the same time maintain 5 the shield across the space bridged by the lace.

In testimony whereof I have hereunto set

my hand in presence of two subscribing witnesses.

GRACE PFEIL.
